TAPE DISPENSER

Alan E. Sherman, St. Louis, Mo., assignor to Superior
Insulating Tape Company, St. Louis, Mo., a corporation of Missouri

Filed Oct. 16, 1963, Ser. No. 76,997

Term of patent 14 years

(Cl. D74—1)

I claim:

The ornamental design for a tape dispenser, as shown.
